UNITED STATES PATENT OFFICE.

JOSEPH LOESER, OF SAN FRANCISCO, CALIFORNIA.

SAW.

Specification of Letters Patent. Patented Mar. 21, 1916.

1,175,963.

Application filed September 28, 1914. Serial No. 363,904.

To all whom it may concern:

Be it known that I, JOSEPH LOESER, a citizen of the United States, residing at San Francisco, in the county of San Francisco and State of California, have invented certain new and useful Improvements in Saws, of which the following is a specification.

My invention relates to new and useful improvements in saws and more particularly to a rotary circular hand saw.

10 The primary object of the invention is the provision of such a saw which is light in construction and easy in operation.

15 A further object is the provision of such a saw having a guard secured thereto to prevent injury while operating.

A still further object is the provision of means for protecting the gears.

20 With these and other objects in view the invention consists in the novel details of construction and arrangement of parts which will be more clearly understood from the following description and drawings, in which,

25 Figure 1 is a side elevation. Fig. 2 is a bottom view partly in section, and Fig. 3 is a fragmental vertical section on the line 3-3 of Fig. 1.

In the drawings, the numeral 1 indicates 30 a guard shield having a handle 2 secured thereto and having the threaded extension 3 for securing the flexible connection for operating the saw. The saw is indicated, at 4, and has an opening in the center thereof 35 through which extends a threaded boss on a plate 5 and secured on the threaded end of the boss is a beveled gear 6. A threaded bolt 7 passes through one side of the shield 1 through the plate and boss 5 and is thread- 40 edly engaged in a socket formed in the opposite side of the shield. This bolt 7 forms the axis upon which the saw rotates. A shaft 8 is mounted in the shield by having an extension 9 entering a socket formed in the 45 shield and the opposite end extending into the extension 3. Secured on the shaft 8 is a beveled gear 10 which is adapted to mesh with the beveled gear 6. A flexible shaft is adapted to be secured to the shaft 8 for rotating the same. Secured to the shield 1 is 50 a cupped plate 11 which extends under the gear 10 and in close proximity to the saw blade 4. The ends of this cupped plate 11 overlap the sides of the beveled gear 10, thereby preventing the accumulation of dirt 55 or any foreign matter on the gear.

By constructing a saw in the above manner I have provided a light saw which may be easily moved from place to place and one in which there is little danger of injury. I 60 have also provided a guard for the beveled gears, thereby preventing the accumulation of foreign matter thereon which would hinder the easy operation of the saw. In assembling the several parts the boss on the plate 65 5 is placed through the opening in the saw and the beveled gear 6 is threaded onto the boss. The parts thus assembled are placed within the shield 1 and the threaded bolts 7 placed in position, thereby securely holding 70 the blade in position and forming an axis for the rotation thereof. The beveled gear 10 is then meshed with the beveled gear 6 and upon the rotation of the shaft 8 the saw will be operated. By having the handle 75 formed on the shield there is no danger of injury while the saw is in operation. Also by providing the cupped plate beneath the gear 10 I have provided against the accumulation of dirt or any foreign matter on the 80 gear.

Having fully described my invention what I claim as new and desire to secure by Letters Patent is:—

1. A saw comprising a casing, a blade having a central opening, a plate having a boss passing through the central opening of the blade, a gear secured on the boss, a bolt passing through the casing and plate secured to the blade forming the axis for the blade, a shaft mounted in the frame, a gear secured to the shaft and meshing with the gear secured to the blade, and means for rotating the shaft.

2. A saw comprising a casing having a handle secured thereto, a threaded extension secured to the casing, a saw blade having a central opening, a plate having a threaded boss adapted to pass through the central opening of the blade, a gear threaded on the boss, a bolt passing through the casing and plate forming an axis for the plate, a shaft mounted in the casing and extending into the extension on the casing, a gear secured to the shaft and adapted to mesh with the gear on the blade, a cupped plate secured to the casing and extending beneath the gear on the shaft, and means extending to the extension for rotating the shaft.

3. A saw comprising a casing having a handle and a portion of reduced width, a threaded extension secured to the casing, a

saw blade having a central opening, a plate having a threaded boss adapted to pass through the central opening of the blade, a gear secured on the boss, a bolt passing through the casing and plate forming an axis for the plate, a shaft mounted longitudinally in the larger portion of the case and extending into the extension on the casing, a gear secured to the shaft and meshing with the gear on the blade, a cupped plate secured

to the casing and extending below and over the sides of the gear on the shaft, and means for rotating the shaft.

In testimony whereof I affix my signature in presence of two witnesses.

JOSEPH LOESER.
